UNITED STATES PATENT OFFICE.

EDWIN E. BAKER AND GUY H. SNAVELY, OF WILLOWS, CALIFORNIA.

COMPRESSED-AIR OILER.

1,260,623.

Specification of Letters Patent. Patented Mar. 26, 1918.

Application filed April 8, 1916. Serial No. 89,940.

To all whom it may concern:

Be it known that we, EDWIN E. BAKER and GUY H. SNAVELY, citizens of the United States, residing at Willows, in the county 5 of Glenn and State of California, have invented certain new and useful Improvements in Compressed-Air Oilers, of which the following is a specification, reference being had therein to the accompanying 10 drawing.

This invention relates to hand oilers, and has special reference to a compressed air oiler wherein air may be first pumped before the discharge valve is open, whereby when 15 this last-mentioned valve is open the oil within the can will be automatically discharged therefrom.

Another object of this invention is the production of a compressed air oiler where- 20 in the pump portion is so carried as to constitute a handle for the oil can and at the same time will constitute an efficient pump for forcing the air into the interior of the can body.

25 Another object of this invention is the production of a simple and efficient valve operating mechanism wherein a sliding plunger is provided which will normally remain in a position to retain the discharge 30 valve in a closed position, but which may be actuated for rotating the valve for allowing oil to be discharged from the can under compressed air force.

With these and other objects in view, this 35 invention consists of certain novel combina- tions, constructions, and arrangements of parts as will be hereinafter fully described and claimed.

In the accompanying drawings:

40 Figure 1 is a side elevation of the compressed air oiler, as constructed in accordance with this invention.

Fig. 2 is a rear elevation of the compressed air oiler.

45 Fig. 3 is a central vertical section through the device.

Fig. 4 is a section taken on the line 4-4 of Fig. 3, looking in the direction of the arrow.

50 Fig. 5 is a fragmentary sectional view through the discharge valve.

Fig. 6 is a top plan view of the plunger used for operating the discharge valve.

55 Referring to the accompanying drawings by numerals it will be seen that the compressed air oiler comprises a cylindrical can

1, having a bottom 2 and a cap 3. The bottom 2 and cap 3 are soldered upon the body 1 so as to form a substantially one-piece hollow can which will constitute the reservoir for the compressed air oiler, which may be filled after removing the screw cap 47. Before the cap 3 is positioned upon the upper portions of the body 1, the partition 4 is positioned within the can so as to extend 60 in an inclined plane, as clearly shown in Fig. 3. A curved tube 5 is also positioned within the can body 1 so as to extend thereabove to be fixedly secured to the inner upper portions of the cap 3. The lower portion of this tube is carried so as to communicate with the opening 6 formed in the partition 4, and is soldered or otherwise secured in position so as to prevent the passage of oil or air between the lower end of 70 the tube 5 and the inner portions of the opening 6. It will further be noted by referring particularly to Figs. 3 and 4 that the partition 4 is provided with an opening 7 adjacent one periphery thereof, so that 75 this opening will be contiguous to the inner portions of the bottom 2.

The pump comprises a hollow casing 8 which is supported at a spaced distance from one side of the can body 1 by means of 85 the supporting bands 9 and 10. These bands 9 and 10 are adapted to be soldered or otherwise secured upon the side portions of the can body 1 so as to fixedly retain the casing 8 in its correct position at a spaced distance 90 from the can body as shown clearly in Figs. 1 and 3. These bands 9 and 10 are similarly constructed and are looped at their outer ends so as to pass about the outer portions of the casing 8 so as to be suitably secured 95 thereon for fixedly supporting the casing 8. This casing 8 is also provided with a cap 11, having an internally threaded rim 12 fitting upon the threaded portion 13 of the casing 8 so as to allow the outer portions 100 of the plunger 14, which is reciprocally mounted within the casing 8, to be efficiently gripped by the cap 11 for preventing the escape of air, as the plunger is moved downwardly. The lower portion of the casing 105 8 is also provided with a base 15 having an internally threaded portion for engaging the lower threaded portion 16 of the casing 8, whereby the base will be efficiently retained in position. This base 15 is also provided with a port 17 which is adapted to be 110 intermittently closed by means of the flap

valve 18. The valve casing 19 is soldered or otherwise secured upon the outer portions of the can body 1, so as to communicate with the opening 20 formed in the can body. 5 This valve casing 19 communicates with the passage 21 formed in the base 15, as clearly shown in Fig. 3. A coiled spring 22 is positioned within this valve casing 19, and bears at one end upon the can body 1 adjacent the opening 20, and at its opposite end upon the ball valve 23, which engages the valve seat 24 formed by the reduction at the inner end of the valve casing 19. It will be seen that as the plunger 14 is moved upwardly air will be sucked into the pump casing 8, since the suction will leave the flap valve 18 open, at which time the ball valve 23 will engage the valve seat 24. As the plunger 14 is moved downwardly, however, 10 the flap valve 18 will swing to close the port 17, whereby the air within the pump casing 8 will pass through the passage 21 urging the ball valve 23 past the spring seat 24 whereby the air may be passed through the 15 opening 20 and into the can body. 20 The gate or discharge valve 25 is carried by the secondary valve casing 26 fixedly mounted upon the upper portion of the cap 3 of the can body 1. This secondary valve 25 casing is provided with a central vertical passage 27 communicating with the tube 5, as shown clearly in Fig. 3. The elongated support 28 is adapted to be mounted upon the upper portions of the secondary valve 25 casing 26 by wedging over the neck 29 thereof, as shown in Fig. 3. This gate valve or discharge valve 25 is provided with a threaded outer end 30 upon which the nut 31 is adapted to be threaded for holding 30 the valve which tapers toward its threaded end, as shown clearly in Fig. 5, in its correct position upon the secondary valve casing 26. An operating pin 32 extends slidably through the opposite end of the valve 35 40 45 50 55 60 65 70 75 80 85 90 95 100 105 110 115 120 125 130 135 140 145 150 155 160 165 170 175 180 185 190 195 200 10795 10800 10805 10810 10815 10820 10825 10830 10835 10840 10845 10850 10855 10860

the body 1 and the inner portions of the cap 3 will be of such strength as to force the oil within the body 1 downwardly. This action will cause the oil to pass through the 5 opening 7, beneath the partition 4, and then upwardly through the tube 5, the passage 27 and through the spout 28. It will be seen that the can may be held in any desired position by gripping the valve casing 8, which 10 will constitute a handle for the compressed air oiler. The spout may, of course, be at any position so that the air may be easily forced directly upwardly to the point desired, such for instance as is often required 15 where the can is in use for assisting in oiling locomotives and like machinery. When the can is in an inverted position while in use, the partition 4 will retain a sufficient quantity of oil between the same and the inner 20 portions of the bottom 2 for ordinary purposes. The oil within the can body at this time will rest upon the cap 3 while the compressed air will pass upwardly against the partition 4, and then through the opening 25 7 for forcing the oil from the can under pressure as hereinbefore set forth.

It will, of course, be noted that the side edge or periphery of the partition engages the inner surface of the can body throughout 30 its entire length. This partition bears upon the bottom adjacent the lower end of the can body, whereby one of the openings in the partition will be carried in very close proximity to the bottom. Since the partition 35 slants away from the bottom of the can body, the portion of the partition adjacent the remaining opening will be spaced at a considerable distance from the bottom. This necessarily makes the partition elongated. The tube 5 engages the partition 40 adjacent the opening farthest from the bottom of the can body. The partition 4 is held against slipping or turning, and it is held in correct position for efficient operation 45 at all times.

From the foregoing description it will be seen that a very efficient compressed air oiler has been produced wherein a pump portion is carried so as to constitute a handle for the compressed air oiler, and furthermore, 50 the pump portion being adapted to provide the can with compressed air, whereby upon the actuating of a certain sliding arm the gate valve may be operated so as to allow the portion of the compressed air within the 55 can to quickly and easily force the oil from the can outwardly from the spout to be discharged at a desired point.

What is claimed is:

In a compressed air oiler of the class described, the combination of a can body having a flat bottom, a slanting partition carried within said can body, said partition having openings formed therein adjacent its periphery and at opposite portions of 60 said partition, a portion of said partition bearing upon said bottom adjacent the lower portion of said can body, one of said openings being carried at a point in close proximity to said bottom, the portion of 65 said partition adjacent the remaining opening bearing upon said can body at a distance from said bottom, the periphery of said inclined elongated partition engaging throughout its entire length the inner portion of 70 said can body, a tube carried by said can body and communicating with the inner surface of said partition by projecting into the opening carried farthest from said bottom, said inclined, elongated partition 75 engaging both said bottom and said tube, whereby said partition will be positively held in a set position within said can body, and means for forcing air into said can body above said partition.

In testimony whereof we hereunto affix our signatures.

EDWIN E. BAKER.
